Fig. 4.

UNITED STATES PATENT OFFICE.

LEWIS A. MAPEL, OF ST. LOUIS, MISSOURI, ASSIGNOR TO AUTOMATIC APPLIANCE COMPANY, OF ST. LOUIS, MISSOURI, A CORPORATION OF MISSOURI.

CONTROLLING DEVICE.

Application filed May 5, 1919. Serial No. 294,957.

To all whom it may concern:

Be it known that I, LEWIS A. MAPEL, a citizen of the United States, residing at the city of St. Louis and State of Missouri, have invented a new and useful Controlling Device, of which the following is a specification.

This invention relates to controlling devices for the automatic control of machines which are independently equipped with electrical apparatus.

An object of my invention is to provide a controlling device for the purpose mentioned, which is of novel and efficient construction and is positive and accurate in operation.

Another object is to provide a controlling device of the character and for the purpose stated, equipped with novel means for varying the interval that the controlled machine or device remains operative or inoperative.

Another object is to provide a controlling device capable of controlling the operative or inoperative condition of a plurality of devices with which the machine is equipped.

An additional object is to provide a controlling device equipped with a time indicator and means under control of the time indicator for causing the controlling devices to function after any desired intervals or periods of time.

Another object is to provide a controlling device equipped with a time indicator and means under control of the time indicator for causing the controlling device to function at any desired time, and manual means for causing the controlling device to function in the absence of the time indicator.

Other objects of the invention will appear from the following description in which reference is made to the drawing illustrating a preferred embodiment of the invention, and in which

Fig. 1 is a front elevation of a controlling device embodying my present invention.

Fig. 2 is a side elevation.

Fig. 3 is a vertical sectional view.

Fig. 4 is a view of the device with the front face or dial plate removed.

Fig. 5 is a view showing the means by

which the timing mechanism controls the controlling device.

Fig. 6 is a detail view illustrating the arrangement of the wiring and the switch device.

Figs. 7, 8 and 9 are detail views illustrating a type of switch mechanism which is adapted especially for use in circuits of high current.

The housing in which the mechanism is mounted is composed of a front portion 1 having a dial 2 in connection therewith; an intermediate portion 3 supporting the timing device 4; and a rear or base portion 5 supporting some of the essential parts of the controlling device which are caused to function by operation of the timing device 4. The main spring arbor or shaft 6 of the timing device extends through the dial plate 2 and is equipped with an indicator or pointer 7 which cooperates with the dial to indicate the periods or intervals of time that may pass from any of the set or adjusted positions of the timing device before the controlling mechanism or device will be affected thereby. The main spring 6 in connection with the shaft 6 is arranged to be energized as an incident to the setting of the timing mechanism for operation for any selected interval of time, and to operate the timing mechanism until the same is stopped at the end of the time interval for which it is set. A knob 8 is loosely mounted on the outer end of the arbor 6 and is movable into and out of clutching engagement with the hub of the pointer 7, so that said knob is capable of manipulation to engage with and turn the arbor 6 in one direction to adjust the pointer 7 at any desired place around the dial, said knob being free to turn in the opposite direction independently of said arbor and pointer.

The device is equipped with means for indicating the process or operations represented by various periods. In the embodiment shown the indicating means comprises indicators 9 and 10 in the form of discs supported by projecting portions of the housing. Each of the discs is provided with several distinctive means of indication; for instance, the disc 9 is provided

with a number of letters A, B, C and D, and the disc 10 is provided with a number of numerals as 1, 2, 3 and 4. Upon a portion of the housing adjacent to the indicator 9 the word "Process" is shown and one of the letters of said indicator is visible through an appropriate opening or window in the housing, thus indicating what particular process is being performed by the machine in connection or association with which the invention is being used.

Assuming that the device is being used in connection with a laundry washing machine, the indicator 9 will be set in position to place the letter "A" thereon opposite the window in the housing when the step in the washing operation designated as process "A" is being performed by the machine. The indicator 10 will be set in such a position that the numeral "1" is exposed to view when the first step in the washing process is being performed. Should the first step of the "process A" require any definite period of time the operator will set the pointer 7 of the time indicator at the point on the dial designating the number of minutes required for such operation and when the pointer turns in an anticlockwise direction to zero on the dial, the controlling device will be operated and the operator in charge of the machine will be notified that the first step in the "process A" has been completed. If the "process A" includes or requires another step the operator sets the indicator 10 in such position that the numeral "2" thereon will be exposed to view through the opening or window and also sets the pointer of the time indicator at the proper place on the dial representing the period or interval required by the second step of the process. By this arrangement the operator in charge of the device may at all times be kept informed concerning what work or process is being performed by the machine in connection or association with which the device is used.

The present invention is designed especially for use in connection or association with machines which are independently equipped with electric apparatus. The invention comprises novel mechanism for controlling the operation of the electric apparatus of the machine in connection with which the invention is used.

The base 5 of the housing is provided with a portion 11 adapted to be connected with a lamp signal 11^a which will operate as a signal, as hereinafter explained.

The housing is formed with a number of conduit outlets for connection with wire conduits leading to different mechanisms. For instance, the conduit outlet 12 affords outlet for the wiring leading to the motor which operates the washing machine; the outlet 13 affords outlet for the wiring for

controlling the electric drain valve of the washing machine; and the outlet 14 affords outlet for the wiring for controlling a signal or other desired cooperative mechanism. At this point it may be appropriate to mention that the wiring passing through the outlet 14 may be in circuit with an appropriate signal mechanism such, for instance, as that disclosed in my co-pending application Serial No. 244,753, eventuating in Patent No. 1,388,278, dated August 23, 1921.

The switch mechanism and the binding posts and connections are supported wholly by the base section 5 of the housing in which a support 15 of insulating material is mounted. The binding posts, 16, 17, 18, 19, 20 and 21 are connected with corresponding contacts 16^a, 17^a, 18^a, 19^a, 20^a and 21^a, respectively, which are in position to make contact with a switch member 22 as required in the operation of the various apparatus or machines controlled through the switch.

The switch member 22 is on a rotary support 23 having a crank 24 in connection therewith whereby the switch may be controlled by the timing mechanism, or manually operated in the absence of the timing mechanism.

The instrument is equipped with a control lever 25 attached to a rod or shaft 26 revolvably supported near the bottom of the device and which constitutes means for manually controlling the different apparatus with which the washer (or other machine) is equipped in order to handle the operation thereof automatically. The inner end of the rod or shaft 26 is journaled in a support 27 which also constitutes an abutment and attachment for the inner end of a spring 28, of the expansion type. The outer end of the spring is connected to a cam member 29 which is attached to the shaft 26.

The power of the spring 28 is exerted to turn the rod or shaft 26 in a counter-clockwise direction and also to actuate said rod or shaft axially in an outward direction. A lever 30 is pivoted upon a support 31 and is actuated in one direction by a spring 32 connecting said lever with a rigid part in the housing. The lever 30 extends into the path of movement of an arm 33 attached to the arbor 6 of the timing mechanism, so that at the proper time the lever 30 will be moved a slight distance by said arm 33 in order to disengage the opposite end of the lever from a shoulder on the cam 29.

Extent of turning movement of the control lever 25 in one direction is limited by a shoulder 34 on the cam member 29 contacting with the detent end of the lever 30, and extent of turning movement of said lever in the opposite direction is limited by an abutment 35 on the housing. The normal idle position of the control lever is that

shown in Fig. 1 in which the lever 30 engages the cam shoulder 34 to which position the control lever is actuated by the power of the spring 28. When said lever 25 is manually turned to position against the abutment 35 the detent end of the lever 30 engages a shoulder 36 (Fig. 5) on the cam 29, thereby holding the switch member 22 in contact with the contact members 16^a, 18^a and 19^a. This closes the circuit to the motor, and starts the washing machine. The control lever is held in that adjustment until shortly before the expiration of the time duration when the lever 30 is automatically released from the shoulder 36 by the arm 33, thus permitting the spring 28 to turn the rod or shaft 26 to position in which a shoulder 37 on the cam 29 is engaged by the detent end of the lever 30. 20 By this operation of the rod 26 the switch member 22 is moved to contact with the contact members 17^a, 19^a and 20^a, thus instantaneously breaking and re-establishing the circuit to the motor, and closing the circuit to the drain valve of the washing machine. The pressure of the arm 33 against the lever 30 is continued by the operation of the timing mechanism after said lever 30 has been released from the first shoulder 36 25 and while the second shoulder 37 is engaged by the end of the lever 30. The switch remains in its second adjustment until the final expiration of the time duration after which the lever 30 is released from the shoulder 37 by the continuing pressure of the arm 33 actuated by the timing mechanism. Thereupon the spring 28 turns the rod 26 to position to actuate the switch 22 into contact with the contact members 18^a, 20^a, and 21^a, thus closing the circuit to the signal mechanism in order to call the attention of the operator to the fact that one operation, or step of an operation 30 has been completed. Turning of the rod 26 or shaft 26 is stopped by contact of the shoulder 38 on the cam with the detent end of the lever 30. The operation of the timing mechanism is stopped by the arm 33 in contact with the lever 30 which is held from further movement by the stop 39.

By pressure on the hub of the control lever the rod 26 may be pressed inwardly in opposition to the power of the spring 28, and the shoulder 38 thereby disengaged 35 from the detent end of the lever 30, thus permitting said spring 28 to turn the rod 26 an additional distance until the cam shoulder 34 is moved into contact with the detent end of the lever 30. In this position the switch 22 occupies the position shown in Fig. 6 in which it is out of contact with all of the contact members.

It is necessary to adjust the timing device before the latch for the control lever 40 will be able to hold the lever in its ad-

justed position. This is true because when the timing device is in its idle or stopped position the arm 33 holds the lever 30 in position to prevent engagement of the detent end thereof with the shoulder 36 on the cam 29, as shown in Fig. 5. In the idle or stopped position of the device the arm 33 holds the lever 30 in the position shown in Fig. 5 so that the shoulder 36 will not engage the detent end of said lever 30, but in said position of the lever 30 the shoulder 36 can not contact with said lever 30.

The switch shown in Figs. 7, 8 and 9 may be satisfactorily used in connection with circuits of either high or low current, whereas the switch shown in Fig. 6 is more particularly adapted for use in circuits of low current. In the switch shown in said Figs. 7, 8 and 9 a member 40 is pivoted upon a binding post 41. The switch member 42 is also pivoted upon the binding post 41 and is movable into and out of contact with the contact members 43 and 44, in order to open and close the circuits by which the different devices of the machine are controlled. The switch member 42 being pivoted upon the binding post 41 is permanently in circuit with one of the wires, and it is only necessary to move the switch member 42 into contact with the contact members 43 and 44, respectively, in order to close the circuits.

A spring 45 connects an extension 46 on the switch member 42 with the member 40 and is operative to throw the switch member 42 out of contact with the contact members 43 and 44, respectively, as an incident to turning of the member 40 from one position to another. Movement of the switch member 42 in one direction is limited by an arm 47 thereon contacting with the member 40. The member 40 has a pin 48 adapted to extend into a slot in the crank arm on the lower end of the rod or shaft 26, so that said member 40 may be swung from one position to another by operation of said rod 26.

In the normal or idle position of the rod 26 the switch member 42 is held out of contact with both contact members 43 and 44. As an incident to turning of the control lever to the right to its position against the abutment 35, the switch member 42 is thrown around by the spring 45 to the position shown in Fig. 7, in which said switch member is in contact with the contact member 44 and bears against an abutment 49. The control lever remains in that adjustment until the expiration of the time duration, when it is automatically released by the operation of the timing mechanism as explained in connection with the form of switch shown in Fig. 6. When the control lever is thus released the spring 28 turns it to position 130

tion in which the shoulder 38 is engaged by the detent end of the lever 30 as an incident to which operation the switch member 42 is thrown out of contact with the contact member 44 and into contact with the contact member 43, thus instantaneously breaking the circuit to the motor and establishing another circuit which leads to the signal mechanism, in order to call the attention of the operator to the fact when one operation, or step of an operation has been completed. The switch remains in its second adjustment and maintains contact with the contact member 43 until the rod 26 is pressed inwardly to disengage the detent from the cam 29, thus permitting the spring 28 to turn the rod 26 an additional distance sufficient to cause the member 40 to move the switch member 42 out of contact with the contact member 43, and to the position shown by dotted lines in Fig. 8.

The form and arrangement of the different parts and elements comprising the invention may be varied without departing from the principle or scope of the invention. I do not confine myself to unessential features, but what I claim and desire to secure by Letters Patent, is:—

1. A controlling device of the character described, comprising timing mechanism settable in different positions to represent different periods or intervals of time, an electric switch operable to open and to close a plurality of electric circuits, a latch for latching the switch in position to close one of the circuits, an element operated by the timing mechanism for releasing said latch and preventing the latch from latching the switch until setting of the timing mechanism, and an actuator for moving the switch to position to open the first-named circuit and to position to close another circuit.

2. A controlling device of the character described, comprising timing mechanism settable in different positions to represent different periods or intervals of time, a plurality of electric contact members in corresponding circuits, an electric switch movable into and out of contact with various ones of the contact members to open and to close a plurality of electric circuits successively, a latch for latching the switch in position to close predetermined ones of the circuits, an element operated by the timing mechanism for releasing said latch successively and preventing the latch from latching the switch until setting of the timing mechanism, and an actuator for moving the switch when said latch is released.

3. A controlling device of the character described, comprising timing mechanism settable to operate for different periods or intervals of time, an electric switch operable to open and to close a plurality of electric circuits, an actuator for moving the switch

from one position to another to open and to close the electric circuits successively, a latch for latching the switch in its different positions and preventing the latch from latching the switch until setting of the timing mechanism, and an element operated by the timing mechanism for releasing said latch.

4. A controlling device of the character described, comprising an electric switch, a rod supported for axial and turning movements, means for operating the switch by the turning movements of said rod, a latch device for holding the rod in the different positions to which it is turned, a settable device preventing operation of said latch until said device has been set and an actuator for turning said rod in one direction and moving said rod axially.

5. A controlling device of the character described, comprising an electric switch, a rod supported for axial and turning movements, a latch device for holding the rod in the different positions to which it is turned when said rod is on one of its axial positions, a settable device preventing operation of said latch until said device has been set and means for moving the rod axially to position in which it will be held by said latch device and for turning said rod in one direction when said latch device is released.

6. A controlling device of the character described, comprising an electric switch, a rod supported for axial and turning movements, a latch device for holding the rod in the different positions to which it is turned when said rod is in one of its axial adjustments, a settable device preventing operation of said latch until said device has been set, means for operating the switch by the turning movements of said rod, and an actuator for moving said rod axially to position in which said rod will be held by said latch device and for turning said rod in one direction when said latch device is released.

7. A controlling device of the character described, comprising an electric switch, a rod supported for axial and turning movements, a latch device for holding the rod in the different positions to which it is turned when said rod is in one of its axial adjustments, a settable device preventing operation of said latch until said device has been set, means for operating the switch by the turning movements of said rod, an actuator for moving said rod axially to position in which said rod will be held by said latch device and for turning said rod in one direction when said latch device is released, and timing mechanism operable to release said latch device after any selected periods or intervals of time.

8. A controlling device of the character described, comprising an electric switch, a rod supported for axial and turning move-

- ments, means for operating the switch by the turning movements of said rod, and an actuator for moving said rod axially in one direction and turning said rod in one direction to position to open the switch.
9. In a controlling device of the character described, an electric switch comprising contact members, a pivoted switch member mounted for turning movements in opposite directions in permanent circuit with an electric circuit wire and being movable into and out of contact with the contact members, stops for limiting turning movement of said member in both directions, a pivoted element, means for moving the pivoted element to different adjusted positions relative to the switch member, and a spring for operating said switch member from one to another of said contact members to close different circuits, each of which includes the wire which is in permanent circuit with said switch member.
10. In a controlling device of the character described, an electric switch comprising contact members, a pivoted switch member in permanent circuit with the electric circuit wire and being movable into and out of contact with the contact members, a pivoted element, means for moving said pivoted element to different adjustments relative to the switch member, a spring for operating said switch member from one to another of said contact members to close different circuits each of which includes the wire which is in permanent circuit with said switch member, and means whereby said pivoted element in one position thereof will hold said switch member out of contact with said contact members.
11. A controlling device of the character described, comprising an electric switch, a rod supported for axial and turning movements and being adjustable in one position to hold the switch open, means for operating the switch by the turning movements of said rod, a latch device for holding the rod in the different positions to which it is turned, timing mechanism, settable to release said latch device after any predetermined period or interval of time and preventing operation of said latch device until the timing mechanism has been set, and an actuator for turning said rod in one direction and moving said rod to position to hold said switch open.
12. A controlling device of the character described, comprising an electric switch, a rod supported for axial and turning movements and arranged to turn in one direction and move axially in one direction to open the switch, a latch device for holding the rod in the different rotative positions in which it is placed, and a spring for imparting axial and turning movements to said rod.
13. A controlling device of the character described, comprising a housing composed of a base portion and a front portion removably connected with the base portion; timing mechanism wholly supported within the housing by one portion of the housing; a support removably mounted in the other portion of the housing; electric switch mechanism mounted on said support; and means supported by the front portion of the housing for controlling said switch mechanism by the timing mechanism.
14. A controlling device of the character described, comprising a housing composed of a base portion and a front portion removably connected with the base portion; timing mechanism wholly supported within the housing by one portion of the housing; a support removably mounted in the other portion of the housing; electric switch mechanism mounted on said support; means supported by that portion of the housing supporting the timing mechanism for controlling said switch mechanism by the timing mechanism; and means whereby the switch mechanism may be operated manually in the absence of the timing mechanism.
15. A controlling device of the character described, comprising a housing composed of a base portion and a front portion removably connected with the base portion; electric switch mechanism supported in the base portion of the housing; timing mechanism supported by the front portion of the housing; and a device whereby the switch mechanism will be controlled automatically by the timing mechanism and affording means for manual operation of the switch mechanism in the absence of the timing mechanism.
16. A controlling device of the character described, comprising settable switch mechanism, a timing device for controlling the switch mechanism, and means whereby the timing device will prevent the setting of the switch mechanism before the timing device is set for operation.
17. A controlling device of the character described, comprising an electric switch movable to open and to closed position, a manual device for moving the switch to closed position, a timing device settable in different positions to represent different periods or intervals of time, and means whereby the timing device will cause the switch to be moved to open position after the expiration of a predetermined period of time, and will prevent setting of the switch in closed position before the timing mechanism is set for operation.
18. In a controlling device of the character described, electric switch mechanism, means whereby said switch may be manually closed, a latch device for holding the switch closed, timing mechanism whose adjustment is necessary before said switch may

- be latched in closed position, and means operable by the timing mechanism for releasing the latch. 40
19. In a controlling device of the character described, an electric switch device, manual means for moving the switch to closed position, a latch for holding the switch closed, and a timing device whose adjustment is necessary before the switch may be latched in closed position, operable to release said latch after a predetermined interval of time. 45
20. In a controlling device of the character described, the combination with an electric switch, manual means for closing the switch, and an actuator for opening the switch, of a timing device whose adjustment is necessary before said switch may be latched in closed position, and means operated by the timing device for releasing said latch after a predetermined interval of time. 50
21. In a controlling device of the character described, the combination with an electric switch, manual means for moving the switch to closed position, and a latch device for setting the switch in closed position, of a timing device whose adjustment is necessary before the latch will hold said switch in closed position. 55
- 30 22. In a device of the character described, the combination of a timing mechanism; manual means for setting said timing mechanism for operation for a selected period of time; means for stopping operation of the timing mechanism at the end of a selected period of time; a switch mechanism; manual means for setting said switch mechanism; means for holding the switch mecha- 60 nism in the position in which it is set; and means controlled by said timing mechanism for operating said switch mechanism at the end of the selected period of time. 65
23. In a device of the character described, the combination of a switch mechanism; manual means for placing the switch mechanism in an adjusted position; an actuator for moving the switch mechanism from the adjusted position; a device for holding the switch mechanism in the adjusted position until released for operation by the actuator; timing mechanism including an actuator therefor which is energized as an incident to the setting of the timing mechanism for operation; manual means for setting the timing mechanism for operation and energizing said actuator; and means operated by the timing mechanism for releasing the switch holding device. 70
24. In a device of the character described, the combination of a switch mechanism; a device for holding the switch mechanism in an adjusted position; means for operating the switch mechanism when said holding device is released; timing mechanism settable for operation for a selected interval of time; means for operating the timing mechanism from any of its set positions and arranged to be energized as an incident to the setting of the timing mechanism for operation; means for stopping operation of the timing mechanism at the end of the selected interval of time; and means operated by the timing mechanism for releasing the holding device of the switch mechanism at the end of said time interval. 75

LEWIS A. MAPEL.
